ELECTRODEPOSITION OF QUATERNARY MAGNETIC ALLOY OF IRON, NICKEL, ANTIMONY AND PHOSPHORUS
 Guy Di Giulio, Philadelphia, and Walter O. Freitag, Conshohocken, Pa., assignors to Sperry Rand Corporation, New York, N.Y., a corporation of Delaware
 No Drawing. Filed Oct. 31, 1962, Ser. No. 234,520
 8 Claims. (Cl. 204—43)

The present invention relates generally to an improved magnetic film particularly adapted for use as a memory element in a data processing system, and more particularly to an improved technique for electrolytically depositing magnetic films of this type which consist essentially of a quaternary alloy of nickel-iron-phosphorus and antimony.

In the preparation of magnetic films which are designed for use in memory applications with data processing systems, it is generally desirable that the films exhibit properties which permit switching at the lowest reasonable energy requirement possible, the energy level being consistent with the stability requirements of the memory core. It is also generally desirable that the film have a composition which provides for a minimal, if any, magnetostriction, in order that any memory element will have suitable stability and consistency, and will operate uniformly in its switching action.

While it has been proposed in the past to prepare electroplated nickel-iron base alloy films for magnetic data-storage devices, these films have normally had high values of H_k , this figure representing the value of the anisotropy field. The values of transverse field required for rotational switching are a function of the H_k value, and for memory devices, low H_k values are desired. In accordance with the technique of the present invention, improved electroplated nickel-iron-phosphorus-antimony magnetic data storage devices may be prepared which have very low H_k values, these values not being sufficiently low, however, to disturb the memory characteristic or capability of the films. In this regard, for films prepared in accordance with the present invention with a useful thickness, the values of H_k normally lie uniformly between the optimum levels of 1.7 and 2.0 oersteds, this value permitting rotational switching of the core at a relatively low magnitude of energy, the entire switching operation being accomplished with a lower overall energy requirement than would otherwise be necessary with films having significantly higher H_k values. In addition, the H_k values are sufficiently high so that the films are not readily disturbed by stray magnetic fields of modest intensity. The system design aspects are accordingly not adversely affected, the films being adapted for use in a variety of conventional film array arrangements.

In addition to the specific values of the anisotropy field H_k , the H_c values are likewise important, this figure relating to the coercive field of the film. Ideally, for most switching operations, the value of H_c should be somewhat less than the value of H_k , the range of the H_c/H_k ratio values preferably being between 0.5 and 1. With this particular ratio range, and with the presently available switching equipment, switching techniques utilized and the like, it has been found that the switching characteristics of a film having these characteristics are very desirable. When the films are "inverted," that is, the value of H_c exceeds that value of H_k , the films produced have been found to generally exhibit poor rotational switching characteristics. In addition, it has been generally found that poor dispersion properties exist in inverted films.

In accordance with the technique of the present invention, an improved electroplating technique is provided

for the formation of thin nickel-iron-phosphorus-antimony films. One important feature of the invention is the provision of a critical range of concentration ratios for the plating constituents in the bath, these concentration ratios being employed in order to prepare the improved nickel-iron-phosphorus-antimony films, these films having the low and controlled values of H_k together with optimum values for the ratio H_c/H_k . Certain conventional nickel-iron solutions which are utilized to prepare electroplated films produce a magnetic member having an unusually high H_k value generally being substantially higher than those achieved in connection with the present invention and ranging up to about 5 oersteds and higher.

In performing the technique of the present invention, nickel sulfate, tartar emetic, ferrous sulfate, together with sodium hypophosphite, are included in an acid plating bath along with certain conventional plating bath additives. These additives including the boric acid, saccharin, sodium lauryl sulfate, and sodium chloride are to be considered as conventional additives only, these being utilized in order to enhance the plating characteristics of and control the ultimate plating of the film, and are otherwise ordinarily used to control or modify the various characteristics of plating. These additives are conventional in the plating art and do not in and of themselves provide a part or portion of the present invention. It will be appreciated that other specific plating additives may be employed to achieve the results of the present invention. The current density employed preferably ranges from between 3 and 10 ma./cm.², and preferably about 6 ma./cm.².

Therefore, it is an object of the present invention to provide an improved solution and electroplating method for the formation of thin nickel-iron-phosphorus-antimony quaternary alloy films, these films having controlled and desirable values of H_k and H_c/H_k ratios and being particularly valuable for use as thin magnetic films for certain memory applications.

It is a further object of the present invention to provide an improved electroplating method for the formation of thin nickel-iron-phosphorus-antimony quaternary films wherein certain critical concentration ratios are employed for controlling the nature of the deposition of electrodeposited film to an optimum degree.

It is yet a further object of the present invention to provide an improved electroplating solution for the formation of thin nickel-iron-phosphorus-antimony quaternary alloy films which are particularly adaptable for use in magnetic memory applications, the electroplating bath including an acid nickel-iron, phosphorus and antimony, and being particularly adaptable for use in plating thin metallic alloy films of these materials.

Other and further objects of the present invention will become apparent to those skilled in the art upon a study of the following specification, and appended claims.

In accordance with the preferred modification of the present invention, the electroplating bath is prepared having a composition range as is indicated hereinbelow:

Component:	Amount, gm./l.
$\text{NiSO}_4 \cdot 6\text{H}_2\text{O}$	218
$\text{FeSO}_4 \cdot 7\text{H}_2\text{O}$	4.0-6.5
NaH_2PO_2	0.2-0.6
$\text{K}(\text{SbO})\text{C}_4\text{H}_4\text{O}_6\frac{1}{2}\text{H}_2\text{O}$	0.05-0.15
Saccharin	0.8
Sodium lauryl sulfate	0.4
NaCl	9.7
H_3BO_3	25

pH of the bath=2 to 5.

Temperature, 22-30° C.

Current density, 3-10 ma./cm.².

In order to achieve the desired current density the potential ranges between about 1.5 volts and 4.8 volts depending on the specimen size. Under these conditions, films having H_k values of between 1.7 and 2.0 oersteds and having H_c/H_k ratios of just slightly less than 1 up to about 1.0 are obtained. The composition of typical films prepared in accordance with these examples are as follows:

Element:	Percentage composition
Nickel	70 to 80
Iron	16 to 28
Phosphorus and antimony	2 to 4

In one typical electroplating operation, a solution having the following composition was employed:

	Gm./l.
$\text{NiSO}_4 \cdot 6\text{H}_2\text{O}$	218
$\text{FeSO}_4 \cdot 7\text{H}_2\text{O}$	6.0
$\text{NaH}_2\text{PO}_2 \cdot \text{H}_2\text{O}$	0.4
$\text{K}(\text{SbO})\text{C}_4\text{H}_4\text{O}_6 \frac{1}{2}\text{H}_2\text{O}$	0.1
Saccharin	0.8
Sodium lauryl sulfate	0.4
NaCl	9.7
H_3BO_3	25

pH of the bath, 1.9.

Temperature, 25° C.

A current density of 6 ma./cm.² was utilized in connection with this bath, and under these conditions the following data is obtained:

Time	H_c (oe.)	H_k (oe.)	Film Thickness, A.
55 seconds	2.0	2.0	1,100

The composition of the films prepared in accordance with this specific example was typically as follows:

Element:	Percentage composition
Nickel	79.5
Iron	17.6
Phosphorus	2.0
Antimony	0.9

Under the conditions outlined above, the film plated for a period of 55 seconds is about 1100 A. in thickness, the film plated for a period of 150 seconds is about 3000 A. in thickness.

Referring now to the individual ingredients in the plating bath, it will be appreciated, of course, that the anion of the nickel and iron salt is not particularly critical, it being appreciated that the ratio of nickel-to-iron in the bath is the critical feature. In this regard, the $\text{Fe}^{++}/\text{Ni}^{++}$ concentration ratio ranges from between about 0.017 up to about 0.028, based upon the normalities of these ions in solution. With regard to the concentration ratio of the antimony ion to nickel, based upon normalities, the ratio $\text{SbO}^{+}/\text{Ni}^{++}$, ranges from between about 0.00009 up to about 0.00027. With regard to the concentration ratio of the hypophosphite ion to nickel, based on normalities, the ratio $\text{H}_2\text{PO}_2^-/\text{Ni}^{++}$ ranges from 0.0011 to 0.0034. It will be appreciated that the various concentration ranges set forth herein will normally enable one to obtain the electroplated thin films in accordance with the present invention, these films having the desirable properties of magnetic thin films for memory applications.

With regard to the normality terms used herein, a 1 N solution of Fe^{++} includes one-half gram-molecular-weight of the salt, for example, FeSO_4 . A 1 N solution of nickel Ni^{++} contains one-half gram-molecular-weight of the salt, for example NiSO_4 ; a 1 N solution of SbO^{+} includes one gram-molecular-weight of the salt, for example, $\text{K}(\text{SbO})\text{C}_4\text{H}_4\text{O}_6 \frac{1}{2}\text{H}_2\text{O}$ antimony is ultimately reduced from an oxidation state of 3 to the free metal,

the normalities as expressed herein do not take account of the ultimate plating reaction through which the antimony goes. The same applies to the phosphorus element. In other words, the term normality as used herein relates solely to the concentration of the various ions of the individual salt solutions with sole reference being to the salt ions or radicals per se.

With regard to the phosphorus and antimony, it will of course be appreciated that the particular cation employed in each case is not critical other than that it should not be a platable cation. For this purpose, any of the alkaline earth metal salts suitable for plating the element phosphorus and the element antimony may be utilized.

The pH of the plating bath has been indicated hereinabove. It will be observed that the bath is mildly on the acid side, this being desirable for plating the films in accordance with the technique of the present invention. The temperature range is not critical, and it will be appreciated that good results may be achieved with holding the bath at substantially or near room temperature.

With regard to the current density employed, it will be observed that the range of between 3 and 10 ma./cm.² has been indicated. It will be appreciated that if a current density substantially lower than the minimum indicated is employed films having a low iron content with negative magnetostrictive properties and a reversal of the magnetic directions may develop. If, on the other hand, a current density is employed which substantially exceeds the maximum indicated hereinabove, films having a high iron content with positive magnetostrictive properties may develop.

The base substrate employed is preferably an insulating substance such as glass or plastic, ordinary micro-slide glass being preferred. The surface of the substrate is initially cleansed of all contaminants, and is preferably polished to present a smooth plating surface. The substrate is then coated with a layer of gold or chromium-gold, the latter including a pair of layers wherein an initial layer of chromium is applied, this being followed by the application of a layer of gold. For example, the substrate surface normally includes a plurality of individually spaced circular plated areas of about 100 A. of chromium followed by 100 A. of gold. Conventional evaporation techniques are employed to coat the substrate. In lieu of an insulated substrate, it is, of course possible to employ a polished metallic surface as a substrate.

When use as a magnetic memory core is anticipated, it is in certain instances, desirable that the film be plated in the presence of an external magnetic field, this field being applied during the plating operation. It has been found that the application of such a magnetic field enhances the uniaxial anisotropy characteristics of the film. In this connection the field is applied to the film being plated along the plane of the film, the field preferably having strength of from about 25 to 35 oersteds.

It will be appreciated that the specific examples listed hereinabove are provided for purposes of illustration only and are not to be otherwise construed as a limitation upon the scope of the present invention. It will be further understood, therefore, that those skilled in the art may depart from these specific examples without actually departing from the spirit and scope of the present invention.

What is claimed is:

1. The method which comprises electrolytically depositing thin magnetic Ni-Fe-P-Sb films onto a substrate to be coated by passing current through an aqueous acidic plating bath consisting essentially of Ni^{++} , Fe^{++} , H_2PO_2^- , and SbO^{+} ions, the concentration of said ions in said bath being particularly characterized in that the $\text{Fe}^{++}/\text{Ni}^{++}$ normality ratio ranges from 0.017 to 0.028, the $\text{SbO}^{+}/\text{Ni}^{++}$ normality ratio ranges from .00009 to

.00027, and the $H_2PO_2^-/Ni^{++}$ normality ratio ranges from .0011 to .0034.

2. The method as set forth in claim 1 being particularly characterized in that the pH of the plating bath ranges from about 2 up to about 5.

3. The method as set forth in claim 1 being particularly characterized in that the current density during deposition ranges from about 3 up to about 10 ma./cm.².

4. The method as set forth in claim 3 being particularly characterized in that the current density is maintained for a level of about 6 ma./cm.².

5. The method as set forth in claim 1 being particularly characterized in that a magnetic field is applied through the film and parallel to a longitudinal axis thereof during deposition.

6. The method as set forth in claim 1, particularly characterized in that the temperature of the bath is maintained between about 22° C. and 30° C. during deposition.

7. An aqueous acidic plating bath consisting essentially of Ni^{++} , Fe^{++} , $H_2PO_2^-$ and SbO^+ ions, the concentration of said ions in said bath being such that the Fe^{++}/Ni^{++} normality ratio ranges from .017 to .028, the SbO^+/Ni^{++} normality ratio ranges from .00009 to .00027, and $H_2PO_2^-/Ni^{++}$ normality ratio ranges from .0011 to .0034.

8. The aqueous plating bath as set forth in claim 7 being particularly characterized in that the pH of the solution ranges from about 2 up to about 5.
